UNITED STATES PATENT OFFICE.

JOHN T. McTARNAHAN, OF BOSTON, MASSACHUSETTS; BY OPERATION OF LAW TO
 RALPH H. CAHOUET, TRUSTEE IN BANKRUPTCY OF McTARNAHAN FUEL OIL
 BURNING CORPORATION, OF BOSTON, MASSACHUSETTS, A CORPORATION OF MASSA-
 CHUSETTS.

AUTOMATIC REGULATOR FOR FUEL-OIL-BURNING APPARATUS.

Application filed September 15, 1922. Serial No. 588,418.

To all whom it may concern:

Be it known that I, JOHN T. McTARNAHAN, a citizen of the United States, residing at Boston, in the county of Suffolk and State of Massachusetts, have invented certain new and useful Improvements in Automatic Regulators for Fuel Oil-Burning Apparatus, of which the following is a specification.

10 The invention to be hereinafter described relates to apparatus for regulating combustion, and more particularly to apparatus employing oil as a fuel.

In generating steam under certain conditions, it is desirable to maintain the steam substantially at a predetermined pressure while the load or steam demand varies.

One of the purposes of the present invention, therefore, is to provide regulating apparatus whereby the supply of fuel oil, and steam or other suitable atomizing agent delivered to the burner or burners, if such agent is employed, may be automatically regulated in response to variations in the pressure of the steam developed by the generator.

Another purpose of the invention is to provide means for automatically regulating the draft for the furnace of the generator in response to variations in the pressure of the steam developed by the generator, and synchronously with the fuel oil regulation, to the end that the air supply may be properly proportional to the fuel supply for economical and most efficient combustion of the fuel.

In order that the pressure of the steam developed by the generator shall not vary substantially from the desired predetermined pressure, it is essential that the regulating apparatus shall be promptly responsive to a slight rise or fall with respect to the predetermined steam pressure. The supply of fuel oil and the atomizing fluid therefor and the draft, should be increased in case the steam pressure drops, but this increase should be so arrested as to avoid raising the steam pressure substantially above the predetermined pressure desired. On the other hand, if the steam pressure rises, the supply of fuel oil and the atomizing fluid therefor and the draft should be reduced, but the reduction should be so ar-

rested as to avoid lowering the steam pressure substantially below the predetermined steam pressure desired.

The construction of the regulating apparatus is such that the supply of fuel oil and the atomizing fluid and the draft are automatically controlled to meet the above requirements.

In carrying the invention into practical effect, a valve is provided for controlling the supply of fuel oil to the burner or burners, and another valve may be provided for controlling the supply of steam or other atomizing agent to the burner or burners, and means is provided for automatically controlling said valves in response to variations in the steam pressure, and means is provided positively to compensate for variations in the steam pressure. That is, if the steam pressure increases, the valve openings are automatically reduced, and the compensating means operates automatically to offset the effect of the increase in steam pressure, thereby to prevent more than a slight closure of the valves. On the other hand, if the pressure of the steam lowers, the regulating apparatus automatically increases the opening of the valves, and the compensating means operates to prevent opening of the valves more than a slight extent.

If the pressure of the steam continues to rise or fall after the compensating means has operated to arrest the reduction or increase in the valve openings, the regulating apparatus operates automatically, progressively, gradually to reduce or increase the valve openings until the boiler pressure has returned to the predetermined pressure desired. The consequence is that the steam pressure is not raised or lowered substantially with respect to the predetermined steam pressure.

In some instances the regulating apparatus may be employed to control the supply of fuel oil and atomizing fluid, and to control the draft for a plurality of boilers. Under certain conditions it may be desirable to shut off one or more of these boilers in accordance with the supply of steam desired. If all of the boilers are to be fired, a greater supply of fuel oil and atomizing fluid will be required, whereas, if one or more boilers is to be shut down, less fuel oil

and atomizing fluid will be required. Another purpose of the invention, therefore, is to provide manually operable means for adjusting the fuel oil and atomizing fluid control valves to regulate the supply of oil and atomizing fluid in accordance with the number of boilers operated.

With the aforesaid and other purposes in view, the character of the invention will be best understood by reference to the following description of one good form thereof shown in the accompanying drawings, wherein:

Fig. 1 is a vertical section through a steam generator equipped with regulating apparatus embodying the invention;

Fig. 1^a is a view of a modified form of the apparatus, in which the regulating valves are employed to control the supply of oil to two sets of burners;

Fig. 2 is a view partly in elevation and partly in vertical section of a portion of the regulating apparatus;

Fig. 3 is a side elevation of the apparatus shown in Fig. 2, certain parts being shown in section;

Fig. 4 is a view partly in elevation and partly in section showing the fuel oil and atomizing fluid regulating valves and a portion of the mechanism for automatically rotatively adjusting the valves; and

Fig. 5 is a plan of a portion of the regulating apparatus.

Referring to the drawings, and more particularly to Fig. 1, a boiler is shown therein of the Babcock & Wilcox type, comprising a drum 1 communicating with a front header 3 and a rear header 5, said headers being connected by inclined water tubes 7 provided with baffles 9 and 11. Beneath the water tubes is the combustion chamber 13 having a front wall 15 and a rear wall 17. The gases of combustion leaving the combustion chamber, cross and recross the inclined water tubes, and leave the boiler through the flue 19 leading to the stack.

A fuel oil burner or burners, such as the burner 21 of well known construction, may project through the front wall 15 of the combustion chamber so as to deliver the fuel and atomizing fluid to the combustion chamber.

The fuel oil may be forced from a suitable source of supply to the burner by the pump 23 connected by a pipe 25 with a valve 27 for regulating the supply of fuel oil, and to be more fully hereinafter described. The valve is connected by a pipe 29 with the burner 21.

The atomizing fluid, in the present instance, steam, may be conducted to the burner from the steam main 31 by a pipe 33 leading to the valve 35 for regulating the supply of atomizing steam, and to be more fully hereinafter described. The valve 35 is connected by a pipe 37 with the burner.

The regulating apparatus may be provided with a suitable support, in the present instance, in the form of a pedestal 39 (Figs. 2 and 3) supporting a base 41 provided with an apron 43 depending therefrom at one side 70 of the pedestal and having a plate 45 with arms 47 and 49 projecting laterally therefrom for supporting the oil and atomizing fluid regulating valves respectively.

The oil regulating valve, in the present 75 instance, comprises a cylindrical casing 51 having a union pipe connection 53 connected to the oil supply pipe 25 and having a union pipe connection 55 connected to the pipe 29.

Mounted in the cylindrical casing 51 is a 80 rotary sleeve valve 57 having diametrically opposed ports 59 and 61 for communication with the union pipe connections 53 and 55, respectively. The valve 57 is fast on a stem 63 projecting through a stuffing box 65 85 mounted on the head 66 of the valve casing 51, said stem being adapted to be rocked by means to be described, for giving the valve 57 rotative adjustment to cause the ports 59 and 61 of the valve to turn with respect to 90 the pipe connections 53 and 55, thereby to vary the effective openings of said ports and regulate the supply of oil.

As stated, in some instances it is desirable 95 manually to regulate the fuel oil valve. To accomplish this, in the present instance, a plug 67 is mounted in the sleeve valve 51 and is prevented from rotating therein by a spline 68. To adjust the plug longitudinally with respect to the sleeve valve to vary 100 the effective openings of the valve ports 59 and 61, a stem 69 may be threaded in a bore in the plug 67, and may extend through a stuffing box 71 mounted on the head of the valve casing 51. The outer end of the stem 69 is provided with a hand wheel 75. The construction is such that the hand wheel may be manually rotated to adjust the plug longitudinally with respect to the sleeve valve to vary the effective openings of the 105 valve ports 59 and 61 as required.

Having described the valve for regulating the supply of fuel oil to the burner, next will be described the valve for regulating the supply of atomizing fluid to the burner.

This valve comprises a cylindrical casing 77 (Figs. 4 and 5) having union pipe connections 79 and 81 respectively connected to the steam supply pipes 33 and 37. Mounted in the cylindrical casing 77 is a sleeve valve 83 having ports 85 and 87 for communication with the pipe connections 79 and 81 respectively. The sleeve valve has a stem 89 secured thereto projecting through the stuffing box 91 mounted on the head 93 of the cylindrical casing, said stem being adapted to be rocked by means to be described, to give the sleeve valve rotative adjustment and vary the relation of the ports 85 and 87 with respect to the pipe connections 79 and 81 130

respectively, thereby to vary the effective openings of said ports and regulate the supply of atomizing steam as required.

As stated, under certain conditions it is desirable manually to regulate the effective opening of the atomizing steam regulating valve. To accomplish this, in the present instance, a plug 95 may be mounted in the sleeve valve 83, and is prevented from rotating therein by a spline 97. To adjust the plug longitudinally with respect to the sleeve valve to vary the effective openings of the ports 85 and 87, a stem 99 may be threaded into a bore in the plug, and may project through a stuffing box 101 mounted on the head 103 of the valve casing 77. Fast on the outer end of the stem is a hand wheel 105. The construction is such that the hand wheel may be manually rotated, thereby to move the plug 95 longitudinally with respect to the sleeve valve so as to vary the effective openings of the ports 85 and 87 to regulate the supply of atomizing steam as required.

Having described the construction of the oil and atomizing steam regulating valves, next will be described means for automatically, rotatively adjusting said valves to regulate the supply of oil and steam to the burner.

This means, in the present instance of the invention, comprises an elongated plate 107 (Figs. 3, 4 and 5) having a groove 109 receiving a cross head 111. Projecting from the cross head are lugs 113 and 115 (Fig. 3) carrying an inclined guide 117 (Fig. 4) adjustably connected to said lugs by bolts 119 and 121 respectively entered through elongated slots 123 and 125 in the terminals of said guide, the construction being such that the guide may be set in different positions of angular adjustment. The stem 63, referred to, for the fuel oil regulating valve, has a crank 127 fast thereon, provided with a roller 129 projecting into an elongated slot 131 of the guide 117.

On the opposite sides of the lugs 113 and 115 from the guide 117, is a guide 133 having elongated slots 135 and 137 through which the bolts 119 and 121 respectively project. The construction is such that the guide 133 may be set in different positions of angular adjustment.

Fast on the stem 89 of the steam regulating valve, is a crank 139 having a roller 141 projecting into an elongated slot 143 in the guide 133. The construction is such that when the cross head is reciprocated by means to be described, the guides 117 and 133 will slide in respect to the crank rollers 129 and 141 respectively, thereby rocking the fuel oil and steam valves to regulate the supply of oil and steam to the burner.

To reciprocate the cross head, a rod 145 may have one end connected to the upper

end of the cross head, and its opposite end connected to an arm 149 secured to the upper end of a piston rod 151 connected to a piston 153 in a cylinder 155 mounted on a housing 157 supported on the base 41 referred to.

To move the piston 153 in the cylinder 155, a pilot valve 159 (Figs. 2, 3 and 5) may be provided, and may communicate with opposite ends of the cylinder 155 through ports 161 and 163. The pilot valve may have a pipe 165 for admitting hydraulic pressure thereto from any suitable source, and the pilot valve may have an exhaust pipe 167 to allow release of the hydraulic pressure.

To control the pilot valve, it may be provided with a stem 169 connected by a yoke 171 with the upper end of a rod 173, the lower end of which is pivotally connected to a beam or lever 175. An end portion of this lever projects into the housing 157, and has lugs 177 provided with knife edges for engagement with a forked bracket 179 secured to and projecting down from the top of the housing.

Mounted in the housing is a diaphragm 181 of rubber or other suitable flexible material, and supported on the diaphragm is a button 183 provided with a knife edge 185 on which rests the lower edge of the lever 175. Beneath the diaphragm is a steam pressure chamber 187 connected by a pipe 189 with the steam main 31 referred to. At a point set in somewhat from the outer end of the lever 175 is pivotally connected a rod 191 having a disk 193 at the lower end thereof for supporting a plurality of weights 195, the number of which may be varied according to conditions as required.

Mounted on the lever is a carriage 197 having wheels 199 adapted to roll along the upper edge of the lever. A rod 201 depends from the carriage and serves to support a plurality of weights 203, the number of which may be varied according to conditions as required. The carriage and weights serve as a poise for varying the effective pressure on the upper side of the diaphragm in opposition to the steam pressure on the under side of the diaphragm.

It is desirable that when the piston 153 is moved downward, the poise shall be moved inward on the lever, and when the piston is moved upward, the poise shall be moved outward on the lever, in order to compensate for variations in the pressure of the steam on the under side of the diaphragm.

To accomplish this, in the present instance, a pair of arms 205 fast on the piston stem 151, are connected to the upper ends of rods 207 which extend downward along the cylinder at opposite sides of the pilot valve and at opposite sides of the lever. The lower ends of said rods are connected to a head 209 having lugs 211 thereon carrying the pin

213 connected to the lower end of a chain 215 or other suitable flexible member. This chain projects upwardly over a roller 217 carried by the housing 157, and the opposite 5 end of the chain is connected to the carriage 197. Also connected to the carriage is a chain 219 or other flexible member which extends over a roller 221 carried by the outer end of the lever, and the opposite 10 end of said chain is connected to a rod 223 carrying a plurality of weights 225, the number of which may be varied according to conditions as required.

In order automatically to regulate draft 15 in response to variations in the pressure of the steam developed by the generator, a damper 227 (Fig. 1) may be provided in the uptake flue 19. This damper may have an arm 229 secured thereto connected by a 20 flexible member 231 with an eye 233 attached to the piston stem 151, said flexible member being guided by suitable rollers 235 and 237. When the piston moves downward it will 25 rock the damper in one direction, and a weight 239 attached to the arm 229 will serve to rock the damper in the opposite direction on upward movement of the piston, thereby automatically to regulate the draft 30 in response to variations in the steam pressure operating through the diaphragm and the compensating mechanism to control the movements of the piston which is connected to the damper.

While the damper is shown herein as 35 mounted in the uptake flue, it will be understood that the damper may be located in the intake for conducting air to the combustion chamber.

The operation of the regulating apparatus 40 will be readily understood from the foregoing description thereof. If the pressure of the steam developed by the generator rises above the desired predetermined steam pressure, the diaphragm 181 will be flexed upward, thereby rocking the beam or lever 175 upward. This movement of the lever will 45 operate through the rod 173 to shift the pilot valve to admit hydraulic pressure into the cylinder 155 at the under side of the piston 153. This will cause the piston to move upward, and the latter through the rod 151 and the rods 207, will let out the chain 215 and enable the weights 225 to operate through 50 the chain 219 to cause the poise to move outward on the lever, thereby increasing the pressure on the diaphragm and causing the latter to flex downward, shift the pilot valve, and cut off the supply of hydraulic pressure 55 to the under side of the piston 153.

The upward movement of the piston will 60 also operate through the arm 149 and rod 145 to move the cross head 111 upward, thereby carrying the guides 117 and 133 upward, and owing to the obliquity of said 65 guides, the cranks 127 and 139 will be given

a rocking movement, thereby adjusting the fuel oil valve 57 and the steam valve 83 to reduce the amount of oil and atomizing steam delivered to the burner. The movements of the valves are slighter than the 70 movements of the piston.

The upward movement of the piston will 75 let off the flexible member 231, and the weight 239 will rock the damper 227 in a clockwise direction to reduce the draft.

On the other hand, if the pressure of the steam developed by the generator drops below the predetermined standard steam pressure, the diaphragm 181 will flex downward, and the lever 175 will rock downward, 80 thereby shifting the pilot valve in a direction opposite to its previous movement, and admitting hydraulic pressure into the cylinder above the piston. This will cause the piston to move downward, and through the 85 rod 151, the rods 207 and the chain 215, will draw the poise inward along the lever, thereby reducing the pressure on the upper side of the diaphragm, and allowing the steam pressure beneath the diaphragm to 90 flex the latter upward and operate the pilot valve to cut off the supply of hydraulic pressure to the upper side of the piston.

The downward movement of the piston 95 will operate through the rod 151, the arm 149 and the rod 145 to move the cross head 111 downward. This will carry the guides 117 and 133 downward, and owing to the obliquity of the latter, the cranks 127 and 139 will be rocked in a direction opposite to their previous movement, thereby to increase the opening of the oil and steam valves 100 so as to increase the amount of oil and steam delivered to the burner.

The downward movement of the piston 105 will also operate through the flexible member 231 and the arm 229 to rock the damper 227 in a contra-clockwise direction, thereby increasing the draft.

In case the movement of the piston is not 110 sufficient to vary the amount of fuel oil and steam delivered to the burner, and to vary the draft to return the steam pressure to the predetermined amount, the piston will progressively and gradually receive movement 115 until the valves and the damper have been properly regulated to bring the steam pressure to the predetermined pressure.

The regulating apparatus is delicately and 120 promptly responsive to variations in steam pressure, so that it does not substantially increase or decrease beyond the predetermined steam pressure desired.

The motive fluid for the piston in the cylinder under the control of the pilot valve, 125 preferably is water, since the latter is positive in its action, and therefore, movements of the pilot valve admitting the hydraulic pressure to the upper or lower side of the piston, will promptly initiate move- 130

ment thereof and promptly effect regulation of the valves and the draft.

The valves and the draft are regulated synchronously, and therefore, the draft will be promptly increased or decreased on increase or decrease in the fuel oil supply, so that the draft will always be properly proportioned in respect to the fuel supply to insure most efficient combustion.

10 It will be noted that the oil and atomizing steam regulating valves are similar in construction and operation, and therefore, they may be employed for controlling the supply of any fluid as required. For instance, if 15 the burners are mechanical burners, that is, of the type in which the atomization or spray of the fuel is accomplished without admitting steam or compressed air into the burner, the pipe leading to the steam valve 20 may be disconnected from the steam main and connected to the oil supply, and the valve may be employed for regulating the oil supply. Under such conditions, one of the valves may be employed to regulate the 25 supply of oil to the burners for one steam generating unit, and the other valve may be employed for regulating the supply of oil to the burners of another steam generating unit.

30 Referring to Fig. 1^a, the valves 27 and 35 are employed for controlling the supply of oil to two sets of burners. A pipe 241 leads from the oil supply to the valve 27, and a pipe 243 leading from said valve is connected by branch pipes 245 with a pair of burners 247. A pipe 249 leads from the oil supply to the valve 35, and a pipe 251 leading from said valve is connected by branch pipes 253 with a pair of burners 255. The 40 construction is such that the automatic regulation of the valve 27 will control the supply of fuel oil to the burners 247, and the regulation of the valve 35 will control the supply of oil to the burners 255.

45 Also, if a mechanical type of burner is employed, under certain conditions the steam regulating valve may be cut out of operation, and the oil valve alone may be employed automatically to regulate the supply of oil to the burner or burners.

50 It will be understood that the invention

is not limited to the specific embodiment shown, and that various deviations may be made therefrom without departing from the spirit and scope of the appended claims.

55

What is claimed is:

1. Apparatus of the character described comprising, in combination, a boiler, a fuel oil burner therefor, pipes for conducting fuel oil and atomizing fluid to the burner, valves for controlling the supply of oil and fluid delivered by the pipes to the burner, a cylinder, a piston therein, a pilot valve for controlling admission of motive fluid to the cylinder to actuate the piston, a stem for the piston, means connected to the stem and having inclined slots therein, connections between said slots and the valves for adjusting the latter on movement of said means, and means responsive to variations in the pressure of the steam developed by the boiler for operating the pilot valve and having provision for promptly automatically compensating for variations in the steam pressure, thereby to restrict the piston to movements of slight extent.

2. An automatic regulator for the feed of oil and atomizing fluid to a burner or burners, comprising, in combination, a support, an oil regulating valve and an atomizing fluid regulating valve mounted on the support, a cylinder mounted on said support adjacent said valves, a piston in said cylinder, a pilot valve for controlling admission of motive fluid to the cylinder to actuate the piston, a stem for the piston, connections between said stem and said oil and atomizing fluid regulating valves including inclined guide and follower means whereby movements of the piston and stem cause adjustments of said valves with slighter movements than those of said piston and stem, and means mounted on said support for operating the pilot valve and adapted to respond to variations in pressure of steam developed by a boiler served by the burner or burners, said means having provision for positively actuating the pilot valve automatically to compensate for variations in the steam pressure and restrict the piston to movements of slight extent.
